UNITED STATES PATENT OFFICE.

HUGH DAVIES AND JAMES COOKE, OF WEST NEW YORK, NEW JERSEY.

INCANDESCENT-LAMP LOCK AND SEAL.

1,070,426.

Specification of Letters Patent. Patented Aug. 19, 1913.

Application filed November 20, 1912. Serial No. 732,432.

To all whom it may concern:

Be it known that we, HUGH DAVIES and JAMES COOKE, citizens of the United States, and residents of West New York, county 5 of Hudson, and State of New Jersey, have invented certain new and useful Improvements in Incandescent-Lamp Locks and Seals, of which the following is a specification.

10 In hotels lighted by electricity and in large office buildings similarly lighted considerable loss results from the theft of incandescent lamp bulbs and particularly of that class of bulbs fitted with tungsten and 15 like expensive filaments. In hotels it frequently occurs that the guests remove the lamp bulbs from the sockets and connect chafing dishes and other electric cooking utensils and electrically heated irons to the 20 light circuit. This frequently results in over-loading the circuit and the consequent burning out of the fuses. Where the fuses are not destroyed there is an excessive consumption of current which is a direct loss to 25 the hotel.

It is the main object of this invention to provide an incandescent lamp socket which will serve as a means for locking the lamp bulb in such manner that it cannot be removed without first breaking the seal and lock.

Another object of the invention is to provide an expansible lamp socket shell which may be expanded to receive the threaded 35 plug of the lamp bulb and then contracted to lock the bulb in the socket and prevent its removal until the locking means is broken or removed to permit the socket shell to be expanded.

40 There are other objects and advantages of the invention which will appear hereinafter.

In the drawing, Figure 1 is an elevation of an incandescent lamp bulb and socket showing the socket shell contracted and sealed to lock the lamp bulb in the socket; Fig. 2 a longitudinal sectional view of the socket shell; Fig. 3 a side elevation of the socket shell; and Fig. 4 an end view thereof.

Referring to the various parts by numerals, 1 designates the lamp socket shell which is split longitudinally from end to end so that it may be readily expanded and contracted. This shell is provided with the usual external head 2, and at its normally open or lamp-receiving end with an outwardly extending annular flange 3. At unit-

able points along the marginal edges of the split portion of the shell are formed outwardly extending ears or lugs 4, said lugs being perforated for the reception of a rivet 5. The marginal edges of the split portion of the shell are overlapped, as shown at 6, so that there will be no open space between such edges. The shell is provided with the usual cap 7 which may be secured thereto 65 in any suitable manner and, of course, within the shell will be placed the usual threaded socket and terminals. As these may be of any suitable construction they are not shown in the drawing.

In operation the shell is first expanded sufficiently to permit the threaded plug on the end of the lamp bulb to be screwed into the usual threaded socket contained in the shell. The shell is then contracted to bring 75 the annular locking flange 3 around the base of the threaded plug. The lugs 4 are then riveted or otherwise permanently connected together to hold the shell in its contracted condition. These lugs may be bent close to 80 the side of the shell, as shown in Fig. 1, or they may be permitted to project outwardly therefrom as shown in the other figures. The cap 7 holds the upper end of the split shell against any tendency to expand it and 85 strongly reinforces it. If desired, when inserting or removing lamps from the shell, this cap may be disconnected from the shell to permit it to be readily expanded.

It will, of course, be understood that any 90 suitable means for contracting the shell and rigidly holding it in its contracted condition may be employed, provided said holding means also acts as a lock and seal to prevent the removal of the lamp bulb until said 95 lock and seal be broken or removed.

What we claim is:

1. An incandescent lamp lock and seal comprising an expansible socket shell, and means at the lamp-receiving end of said shell 100 to lock the lamp therein when said shell is contracted, and means for holding said shell contracted.

2. An incandescent lamp lock and seal comprising an expansible socket shell 105 formed with an inwardly extending locking flange at its lamp-receiving end, and means for holding said shell contracted whereby the locking flange will prevent the removal of the lamp bulb from the socket. 110

3. An incandescent lamp lock and seal comprising a longitudinally split socket

shell formed with an inwardly extending locking flange at its lamp-receiving end, and removable means for rigidly holding the socket shell against expansion.

5 4. An incandescent lamp lock and seal comprising a longitudinally split socket shell, an inwardly extending locking flange at the lamp-receiving end thereof, outwardly extending lugs formed along the
10 edges of the longitudinal division in the

shell and adapted to be riveted together to contract the shell.

In testimony whereof we hereunto affix our signatures in the presence of two witnesses this 16th day of November 1912.

HUGH DAVIES.
JAMES COOKE.
